PER

UNITED STATES PATENT OFFICE.

EDWARD POOLE, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,798, dated April 16, 1872.

Specification describing a new and original Design for a Carpet, invented by EDWARD POOLE, of Halifax, in the county of York, England.

The accompanying photograph fully illustrates my new design.

This invention relates to a new carpet design, which contains a new scroll for the main groundwork and a new form of border.

The scroll is worked on a plain background and has a thorny appearance, owing to numerous fine projections, as shown. The border

consists of alternate larger and smaller ovals, formed by two intersecting undulating lines, and has small rosettes or flower-pieces within each oval.

I claim as my invention—

The design for a carpet, containing the scroll-work and border, as shown and set forth.

EDWARD POOLE.
